W. D. EVERLY,
ENGINE STARTER,
APPLICATION FILED AUG. 19, 1913.

1,145,130.

Patented July 6, 1915.

UNITED STATES PATENT OFFICE.

WILLIAM D. EVERLY, OF SANGER, TEXAS.

ENGINE-STARTER.

1,145,130.

Specification of Letters Patent.

Patented July 6, 1915.

Application filed August 19, 1913. Serial No. 785,538.

To all whom it may concern:

Be it known that I, WILLIAM D. EVERLY, a citizen of the United States, residing at Sanger, in the county of Denton and State 5 of Texas, have invented a new and useful Engine-Starter, of which the following is a specification.

The device forming the subject matter of 10 this application is a crank adapted to be employed for starting engines of the internal combustion type.

One object of the invention is to provide 15 novel means for operatively connecting the crank with the engine shaft.

Another object of the invention is to provide 20 novel means whereby, should the engine back-fire, the handle will be automatically detached from the remaining portions of the crank.

It is within the scope of the invention to 25 improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of parts claimed without departing from the spirit of the invention.

In the drawing:—Figure 1 shows the invention in elevation; Fig. 2 is a longitudinal section on the line 2—2 of Fig. 1; Fig. 3 is a transverse section through the drum portion of the device; Fig. 4 is a perspective showing the spring constrained shoe and attendant parts; Fig. 5 is an elevation showing the lever portions of the structure at right angles to each other, as in the case of a back-fire, parts being broken away; Fig. 6 is a fragmental perspective showing a portion 45 of the shoe-carrying spring.

In the accompanying drawings, the numeral 1 indicates the shaft of an internal combustion engine, the shaft 1 including a reduced extension 2 terminating in a threaded tip 3 carrying a washer 4 and a nut 5. A drum 6 is shown and includes a sleeve 7 mounted to rotate on the shaft 1.

Fulcrumed intermediate its ends upon the extension 2 of the shaft 1 is a primary lever 8. Disposed between the primary lever 8 and the open side of the drum 6 is a closure plate 9. Studs 10 and 11 project from the primary lever 8 through the closure plate 9 and enter the drum 6.

Disposed within the contour of the drum 6 and keyed as indicated at 12 to the engine shaft 1 is a ratchet wheel 14, adapted to be engaged by a pawl 15 which is fulcrumed intermediate its ends on the stud 11. To one end of the pawl 15 links 16 are pivoted, the 65 links 16 being pivoted to a shoe 17 which is adapted to engage the periphery of the drum 6. The shoe 17 is secured to one end of a spring strip 18 and the other end of the spring strip, indicated at 19 is free. The 70 spring strip 18 is located within the periphery of the drum 6 and is put under tension before it is inserted into the drum, so that the strip will exercise a friction drag on the drum. An ear 20 is secured to the strip 75 18 and one end of a retractile spring 21 is secured to the ear, the other end of the spring being connected with the stud 10 which constitutes a part of the primary lever 8. The primary lever 8 terminates at 80 its free end in an enlarged head 22 having a circular opening 23. There is a notch 23^a in one edge of the head 22, the notch leading into the circular opening 23. The width of the notch 23^a is less than the diameter of the 85 circular opening 23.

The invention further includes a secondary lever 24 from which projects a headed pin 25. As clearly shown in Fig. 5, this pin 25 is of unequal transverse dimensions. 90 The major transverse dimension of the pin approximates the diameter of the opening 23, the minor transverse dimension of the pin being slightly less than the width of the notch or slot 23^a. For a specific delineation 95 of this portion of the pin, note the point at which the reference character 26 is applied in Fig. 5. At its outer end, the secondary lever 24 is equipped with a handle 27 adapted to be engaged by the hand of the operator. At its inner end, the secondary lever 24 terminates in a socket 28 in which a pin 30 is inserted through the

pawl 29 and is mounted to move in longitudinal slots 31 formed in the socket 28. The movement of the inner end of the secondary lever 24, in one direction, is limited by a stop 32 on the primary lever 8. Projecting from the primary lever 8 is a pin 33 upon which is fulcrumed a latch 34. The latch 34 and the inner end of the pawl 29 are provided with interlocking parts 35. 5 The latch 34 includes a finger 36 extended longitudinally of the primary lever 8 and located between lugs 37 constituting a part of a yoke 38 secured transversely to the primary lever 8. Obviously, the lugs 37 may 10 be formed directly upon the lever 8. This minor change is a mechanical detail unworthy of illustration and readily understood by any skilled mechanic. A bolt 39 is mounted in the lugs 37 and extends through 15 the finger 36 of the latch 34, the bolts being provided at one end with a nut 40 which, engaging one lug 37, holds the bolt in place. A compression spring 41 surrounds the bolt 39 and bears against the finger 36 of the latch 20 34. The degree of compression in the spring 41 may be regulated by an adjusting nut 42 which is threaded onto the bolt 39.

Presupposing that the parts are positioned as shown in Fig. 1, the operation of 25 the device is as follows:—If the handle 27 is moved in the direction of the arrow A in Fig. 1, the pin 25 will not move out of the slot 23^a because the major transverse dimension of the pin is greater than the width 30 of the slot and stands transversely of the slot. The pin 25 therefore acts as a fulcrum, and the inner end of the pawl 29 remains 35 interlocked, as shown at 35, with the latch 34, the spring 41 preventing the finger 36 40 of the latch from moving to an extent sufficient to break the interlocked engagement between the pawl 29 and the latch 34, as shown at 35. Thus, the lever 8 will be 45 swung in the direction of the arrow A, the lever 8 rotating on the extension 2 of the engine shaft 1. When the lever 8 swings in the direction of the arrow A, the stud 11 which constitutes a part of the lever will 50 carry with it the pawl 15. Through the medium of the spring strip 18 (which exerts a friction drag), the shoe 17 and the links 16, the pawl 15 will be tilted so that it will 55 interlock with the ratchet wheel 14. The lever 8 and attendant parts are thus coupled up operatively with the engine shaft 1, and the same will be rotated in the direction of the arrow A to effect the starting of the engine.

So soon as the engine is in operation and 60 the shaft 1 is rotated, the ratchet wheel 14 will click over the pawl 15. When the hand of the operator is released from the handle 27, the spring 21 will tilt the lever 8 on the extension 2 of the engine shaft 1 to an ex-

tent sufficient to disengage the pawl 15 from 65 the ratchet wheel 14.

Should the engine back-fire during the cranking operation, the lever 8, under such circumstances, moving in the direction of the arrow B in Fig. 1, the spring 41 will 70 yield to an extent sufficient to permit interlocking engagement between the pawl 29 and the latch 34 to be broken. Then, in the first instance, the secondary lever 24 will stand crosswise of the primary lever 8 as 75 shown in Fig. 5. Thus, the minor transverse dimension of the headed pin 25 will be disposed transversely of the notch 23^a, as shown in Fig. 5. As the primary lever 8 continues to move in the direction of the arrow B, the pin 25 will pass out through the notch or slot 23, and thus the secondary lever 24 will 80 be detached from the primary lever and will remain in the hand of the operator.

The compressive effort of the spring 41 85 may be adjusted by rotating the adjusting nut 40 on the bolt 39. The function of the stop 32 is to prevent the inner end of the secondary lever 24 from swinging too far in the direction of the arrow A after the 90 interlocking parts 35 of the pawl 29 and the latch 34 have been disposed in engagement as shown in Fig. 1.

Having thus described the invention, what 95 is claimed is:—

1. In an engine starter, a shaft; a drum journaled thereon; a ratchet wheel secured to the shaft and located within the drum; a lever mounted to swing on the shaft; a pawl pivoted to the lever and adapted to 100 engage the ratchet wheel; a spring strip within the drum and frictionally engaged therewith, one end of the strip being free and independent of the pawl and bearing upon the drum; a link forming a pivotal 105 connection between one end of the pawl and the other end of the spring strip; and a retractile spring connecting the lever with the spring strip at a point spaced from the free end of the spring strip. 110

2. In an engine starter, a primary lever provided with an opening and with a reduced slot communicating with the opening; a secondary lever comprising a pin of unequal transverse dimension, the major transverse dimension of the pin being greater than the width of the slot and the minor transverse dimension of the pin being less than the width of the slot, whereby the pin 115 may move through the slot when the levers stand at an angle; and releasable means for holding the levers in approximate alinement. 120

3. In an engine starter, a primary lever; shaft-engaging means carried by the primary lever; a secondary lever having a 125 handle; a single means for connecting the secondary lever pivotally with the primary lever only, said means being automatically

detachable from one lever along with the other lever, when the levers stand at an angle to each other, thereby to permit a complete separation of the levers; and automatically releasable latch mechanism connecting the levers against relative pivotal movement.

In testimony that I claim the foregoing as

my own, I have hereto affixed my signature in the presence of two witnesses.

WILLIAM D. EVERLY.
